United States Patent Office

Des. 218,910
Patented Oct. 6, 1970

218,910

PUNCH RETAINER

Robert J. Gargrave, 4717 James Hill Road,
Dayton, Ohio 45429

Filed June 16, 1969, Ser. No. 17,731

Term of patent 14 years

Int. Cl. D15—99

U.S. Cl. D55—1

FIG-8

FIG-9

FIG-11

FIG. 1 is a top perspective view of a punch retainer showing my new design;

FIG. 2 is a bottom perspective view thereof;

FIG. 3 is a top plan view thereof;

FIG. 4 is a bottom plan view thereof;

FIGS. 5, 6 and 7 are elevation views showing the respective sides thereof;

FIG. 8 is a top perspective view of a slightly modified version of the design illustrated in FIGS. 1 through 7; and

FIGS. 9 through 11 respectively show modifications of my design as to the peripheral configuration thereof.

I claim:

The ornamental design for punch retainer, substantially as shown and described.
